UNITED STATES PATENT OFFICE.

LEON LAZAR, OF NEW YORK, N. Y., ASSIGNOR TO LAZAR HOLDING CORPORATION, OF NEW YORK, N. Y.

LIGHTING FIXTURE.

Application filed April 15, 1925. Serial No. 23,303.

My invention relates to improvements in shadowless lighting fixtures for dental offices, operating rooms, and the like.

The principal object of the invention is to provide a lighting fixture, particularly adapted for dental use, which comprises a plurality of adjustably mounted lights and means for simultaneously concentrating the rays from each light at a common point. 10 A further object of the invention is to provide a lighting fixture of this character with a universal supporting bracket, the latter co-operating with said means for controlling the lights, to enable an operator to locate the concentrated light rays at substantially any plane or elevation required by lighting fixtures of this character.

Further objects of the invention will appear in connection with the following description and in the accompanying drawings, in which,

Figure 1 is a front elevational view of my improved lighting fixture showing an installation of four lights; Figure 2 is a side elevational view of the fixture showing the parts on a larger scale and partly broken away to disclose otherwise hidden parts; Figure 3 is a detail view of the control cam for the lights; Figure 4 is a detail plan view of the universal connection for supporting the fixture; Figure 5 is a view similar to Figure 2 showing a modified control for adjusting the lights; and Figure 6 is an elevational view of the same.

Referring to the drawings and particularly to Figures 1 to 4, 10 denotes a tubular base support and 11 a tubular stem adjustable in said base. The stem 11 may be of any convenient length, preferably reaching an elevation well above the seat of a dental chair, for instance. An elbow 12 is carried by the upper end, and supports a lateral yoke portion 13, between the parallel arms 14 of which fibre washers 15 are arranged, the latter embracing the shank 16 of a union 17. From the opposite side of the union, projects an upright shank 18 which is therefore disposed at right angles to the shank 16 and receives the yoke portion 19 of a tubular member 20. 50 Similar fibre washers are disposed between the yoke portion 19 and interposed shank 18. Both of the yoke portions 13 and 19 and their respective shanks 16 and 18 are pivotally connected by means of bolts 21. The tubular

member 20 is open at its outer end and a stub 55 pin 22 is rotatably carried in the bore. The member 20 is further provided with a tangentially disposed pin 23 which is partially embraced by the walls of a continuous groove 24 cut in the periphery of the stub pin 22. 60 This construction will enable the pin 22 to rotate without becoming detached from the tubular member 20. The structure thus far described relates only to the universal connections for the fixture and it will be clear 65 that lateral and vertical arcuate adjustment may be effected by the connection with the union 17, while any circular adjustment required for the fixture may be taken care of by the tubular support for the stub pin 22. 70

Referring now to the lighting fixture, 25 denotes a cover plate disposed on the end of the pin 22, the plate 25 being detachably connected to a housing 26, which comprises a rectangularly shaped hollow member having its two side walls and top and bottom walls provided with exteriorly threaded extensions 27 having axial bores 28. The front wall of the housing 26 is similarly provided with an extension 29 having a threaded bore 80 30 to receive a threaded shaft 31 capable of being adjusted axially by rotation thereof. The inner end of the shaft 31 carries a cone shaped cam 32 and the outer end supports a sprocket wheel 33. 85

Each threaded extension 27 carries a tubular extension arm 34 interiorly threaded at both ends, and at the outer end thereof is arranged a collar or cap 35 from which projects the arms of a yoke 36. Pivotedly 90 mounted between the arms of the yoke 36 is a light comprising a cylindrical casing 37 having a condenser lens 38 at one end and an electric socket 39 at the other. Assuming that the normal position of a casing 37 is on the horizontal, as illustrated in Figure 2, any adjustment of the light about its pivot to concentrate its light rays on a desired point is accomplished by a mechanism comprising a U-shaped bracket 40 attached to the periphery of the casing 37 adjacent and between the arms of the yoke 36. The upright portions 41 of the bracket are disposed longitudinally of the casing and are provided with parallel slots 42, the longitudinal axis of 100 which are inclined outwardly towards the condenser end of the casing.

Yieldably mounted in the extension arm

34 and projecting axially throughout the length of the latter is an adjustable rod 43, the inner end thereof being extensible in the bore 28 and terminating in a round end 44 which is yieldably held in engagement with the surface of the cone-shaped cam 32. The opposite end of the rod 43 carries a connection 45 which projects between the ears 41 and which is provided with oppositely projecting pins 46 disposed loosely in the slots 42. The rod 43 is normally held against the inclined surface of the cam 32 by a coil spring 47, one end thereof being seated against a washer 48 arranged in the outer threaded end 15 of the extension 34 and the other end yieldably engaging against a washer 49 fixed to the rod 43 at a point spaced substantially from the inner end. When the light casing 37 is on the horizontal plane, shown in Figure 20 2, the pins 46 are disposed in the low end of the openings or slots 42 and as the cone shaped cam 32 is withdrawn outwardly the rods 43 follow inwardly and towards the center of the housing 26. This operation causes the 25 pins 46 to ride upwardly in the slots 42 and consequently rock the light casing 37 about its pivotal support in the yoke member 36. Since each light depends upon the cam 32 to enable the individual springs 47 to act upon the rods 30 43, the relative movement of each light will be exactly the same. Then, at a mid point where the axis of the light intersect, a highly illuminated disc of light will appear upon any object upon which the disc of light is 35 focused.

The control for any movement of the lighting fixture including the focusing device, comprises a collar 50 which may be attached to anyone of the extension tubes 34, and which 40 is provided with a projection and stub-bearing pin 51. Rotatably mounted on the pin 51 is a handle 52 having a grip 53 at its outer free end and a sprocket wheel 54 at the inner end adjacent the collar 50. The sprockets 54 45 and 33 are aligned to receive an endless sprocket chain 55. It will be clear that any rotary adjustment of the handle 52 will impart an axial movement to the shaft 31 thereby changing the position of the cam 32 as 50 already explained. Simultaneously with this rotary adjustment, the handle may be made to move the entire fixture and consequently regulate the intersecting axis of the lights at any convenient location.

55 Referring now to the modified embodiment of my invention, illustrated particularly in Figures 5 and 6, it will be clear that the mechanism at the outer ends of the extensions is identical with that used in connection 60 with the preferred form, except that the connection 45 is provided at its inner end with a cylindrical portion 56 having a threaded bore 57 to receive the threaded end of a rod 58 projecting through the extension tube 34. 65 It is intended, according to this construc-

tion, that the normally upright extension tubes 34 will remain permanent and in that case the rod 58 will extend through two extensions. A housing 59 supports the extensions 34 and is provided with detachable side 70 cover plates 60 which may carry a second pair of extension tubes 34, projecting at right angles to and on the same plane with the upright pair. The shaft or rod 58 in this construction merely rotates and carries a miter gear 61 within the housing 59, the gear 61 meshing with two oppositely disposed miter gears 62 which are fixed to the ends of rods 63, the latter being disposed axially of the horizontal extensions and adapted to operate 80 lights arranged at the ends of the same. In order to impart axial movement to the cylindrical portions 56 at the ends of the extensions, the rods 58 and 63 are rotated through their miter gear connections with the upright 85 rod 58, which is rotated by a handle connection similar to that already described in connection with the preferred form, that is in so far as the mounting and rotary shaft 51 is concerned, but in the modified embodiment the shaft 51 is offset to one side of the extension 34 and carries a pinion gear 64 in mesh with a pinion gear 65 fixed on the rod or shaft 58. The housing 66 for the handle connection may be of any suitable 90 design; in the present instance, however, I have divided the extension 34 and inserted therebetween a casting having flanged portions to receive and be secured to similar flanges 67 carried by the adjacent ends of the 95 extension.

It will be clear that in either embodiment of my invention the two horizontal extensions and their lights may be removed by simply detaching the extensions from the housings 100 and substituting for the cover plates other plates which do not include the projections for receiving the extensions.

The operation of the device is substantially as follows:

It will be assumed for the present purpose that the fixture is arranged within easy reach of a dentist who has a patient seated in the usual dental chair with the head tilted back to bring the mouth in correct position. The 115 handle 52 is rotated by one hand of the dentist until all of the lights are directed approximately towards a common center. The fixture as a whole is then tilted about its universal connection by bearing, in the desired direction, upon the handle. Further rotary adjustment of the handle should then bring the discs of light from each light into register, all of which will result in a plurality of disc-shaped illuminated spots superposed in the mouth of the patient. It will be clear that since the light rays are directed from more than one angle, the mouth 125 will still remain illuminated in the event that an object obstructs one of the light sources. 130

It will be further clear that lighting fixtures of this character may be carried by suitable apparatus either supported on the dental chair or upon a special arm attached to any of the standard units used in dental office for carrying the engine, fountain, instrument table, etc.

What I claim and desire to secure by Letters Patent is:

10 1. A lighting fixture of the character described, comprising a housing mounted for rotary adjustment, a plurality of spot lights carried by and spaced from the housing, and means disposed in the housing and connected to the spot light for simultaneously adjusting said spot lights to concentrate their rays at a relatively close common point.

20 2. A lighting fixture of the character described, comprising a plurality of adjustable spot lights arranged as a unit, means for simultaneously adjusting said spot lights towards a relatively close common center, means mounted for rotary adjustment and for supporting said unit, and universal connecting means between the unit and supporting

25 3. A lighting fixture of the character described comprising a housing mounted for rotary adjustment, a plurality of adjustable spot lights carried by and spaced from the housing, means for adjusting said spot lights towards or away from a relatively close common center, and a supporting frame for said housing, comprising a collapsible column, and a universal connection for one end of said column connected with said fixture.

40 4. In a lighting fixture of the character described, the combination of a supporting frame, a housing mounted for rotary adjustment on said frame, radially disposed members carried by said housing, adjustably mounted spot lights carried by said members, and means for simultaneously adjusting said lights relative to a common center and appropriately close objective.

45 5. In a lighting fixture of the character described, the combination of a supporting frame, a housing mounted for rotary adjustment at the end thereof, radial arms attachably carried by said housing, a spot light adjustably mounted at the end of each arm, axially adjustable connection at the ends of said arms and connected to said lights, and means disposed in said housing and co-operating with said connections to simultaneously adjust all of said lights relative to a common center.

60 6. In a lighting fixture of the character described, the combination of a supporting frame, a housing at the end thereof, radial extensions attachably carried by said housing, adjustable spot lights carried by said extensions, means disposed within said housing and co-operating with the spot lights to simultaneously adjust the latter relative to a

common center, and means carried by one of said extensions to control said last named means.

7. In a lighting fixture of the character described, the combination of a housing mounted for rotary adjustment, radial extensions therefor, adjustable spot lights for said extensions, means disposed in said housing and radial extensions to simultaneously adjust said lights to concentrate or spread their rays on a relatively close objective, and a handle operatively connected to said last named means.

8. In a lighting fixture of the character described, the combination of a supporting frame, a universal unit at the end thereof, a housing carried by said unit, radial extensions for said housing, adjustable spot lights for said extensions, means disposed in said housing and operatively connected to said lights for imparting simultaneous adjustment to each light, and a handle control attached to one extension and operatively connected to said last named means.

9. In a lighting fixture of the character described, the combination with a housing mounted for rotary adjustment and having radially spaced extensions, a yoke at the end of each extension, of a spot light pivotally arranged in said yoke, and means axially adjustable in said extension and connected to the light to adjust the axis of the latter.

10 10. In a lighting fixture of the character described, the combination with a housing mounted for rotary adjustment and having radially spaced extensions, a yoke for each extension, a spot light pivotally arranged in said yoke for concentrating or spreading their rays on a relatively close objective, comprising a casing having a projection provided with inclined slot, a rod adjustable in said extension and having a projection disposed in said slot, whereby relative adjustment of said projection will cause the casing to rock and change the relative position of the axis of the spot light.

11 11. In a lighting fixture of the character described, the combination of radially disposed adjustable spot lights, extensions supporting said lights, a housing mounted for rotary adjustment to support said extensions, rods disposed in said extensions and operatively connected at their outer ends to rock said lights to concentrate or spread their rays over a relatively close objective, and means disposed in said housing and engaging said rods to impart simultaneous movement thereto to adjust said lights relative to a common center.

12. A lighting fixture, comprising a housing, radial extensions therefor, adjustable spot lights for the ends of said extensions, and means for adjusting said lights comprising a cone shaped cam adjustable axially thereof in said housing, yieldably supported

rods disposed in each extension and normally engaged with the surface of said cam, and connecting means between the axially adjustable rods and said lights.

5. 13. A lighting fixture, as claimed in claim 11, including a handle control carried by one extension, and means connecting said handle

to the rod within the extension, whereby rotation of the handle will rotate the rod.

In testimony whereof, I have signed my name to this specification this 14 day of April, 1925.

LEON LAZAR.
